UNITED STATES PATENT OFFICE

109,541

DESIGN FOR AN AUTOMOBILE RADIO ANTENNA

George O. Benson, Niagara Falls, N. Y.

Application December 4, 1937, Serial No. 73,381

Term of patent 7 years

To all whom it may concern:

Be it known that I, George O. Benson, a citizen of the United States of America, residing in Niagara Falls, county of Niagara, State of New York, have invented a new, original, and ornamental Design for an Automobile Radio Antenna, of which the following is a specification, reference being had to the accompanying drawing, forming a part thereof.

Figure 1 is a perspective view of an automobile radio antenna, showing my new design.

Figure 2 is a side view of an automobile radio antenna, showing my new design.

I claim:

The ornamental design for an automobile radio antenna, substantially as shown.

GEORGE O. BENSON.
